DRILL BIT

Feri A. Thaheld, Dallas, Tex., assignor to The
Guiberson Corporation, Dallas, Tex., a corpora-
tion of Delaware

Application August 1, 1935, Serial No. 34,180

9 Claims. (Cl. 255—71)

This invention relates to new and useful im-
provements in drill bits.

One object of the invention is to provide a drill
bit having improved means for rotatably secur-
ing the usual cutters thereon.

An important object of the invention is to pro-
vide a drill bit having cutter axles for receiving
conical cutters, together with rollers for rotatably
fastening the cutters on said shafts, each roller
having an undulating or corrugated surface,
whereby said corrugations not only serve to hold
the cutters in place but also provide an increased
surface for bearing the thrust during the cutting
operation.

Another object of the invention is to provide
an improved drill bit having inclined axles for
carrying the cutters, each axle and the bore of its
cutter being formed with annular corrugations,
whereby rollers having complementary corruga-
tions may be inserted between the axle and cutter
to rotatably confine said cutter on the axle, the
rollers being readily removable which makes for
easy and quick assembling and dismantling of the
drill bit.

A still further object of the invention is to pro-
vide an improved drill bit structure wherein the
axles on which the cutters are mounted, are made
separate from the bit body and may be readily
welded, or otherwise fastened thereto, which
permits the cutters to be mounted on their axles
prior to the securing of the axles to the bit,
whereby the mounting of the cutters may be more
readily accomplished and the entire assembling
simplified.

A construction designed to carry out the in-
vention will be hereinafter described, together
with other features of the invention.

The invention will be more readily understood
from a reading of the following specification and
by reference to the accompanying drawings, in
which an example of the invention is shown, and
wherein:

Figure 1 is a view partly in elevation, and partly
in section of a drill bit, constructed in accordance
with the invention,

Figure 2 is an enlarged cross-sectional view,
taken on the line 2—2 of Figure 1.

Figure 3 is a view, partly in elevation and partly
in section of another form of the invention,

Figure 4 is an elevation taken at right angles
to Figure 3,

Figure 5 is an isometric view of the bit body
and one of the axles, and

Figure 6 is a vertical, sectional view of one of

the cutters showing the direction of thrust
thereon.

In the drawings, the numeral 10 designates a
bit body or head having a reduced, tapered pin
11, or other drill stem connection at its upper end. 5
The lower end of the pin is surrounded by an
outwardly directed shoulder 12. The body is pro-
vided with depending legs, or hangers 13 which
have their inner sides 13' inclining inwardly and
upwardly toward the center of the body (Figure 10
1). Each hanger is provided with an inwardly
extending inclined cutter axle or shaft 14, the
axles being disposed at substantially a right angle
to the inner surface 13' of the hanger. It is noted
that the axles are in the same horizontal plane 15
and are diametrically opposite each other.

The outer surface of each axle is formed with
annular ridges or corrugations 15 which are
spaced apart and cover substantially the entire
length of said axle. The lower, outer edge of each 20
axle is beveled at 16 and this bevel is provided with
an annular recess or groove 16', which is semi-
circular in cross-section. A conical cutter 17 is
mounted on each axle and each cutter is provided
with suitable cutting teeth 18 on its exterior sur- 25
face. The teeth are shown extending longitudi-
nally of the cutter, but it is pointed out they may
be of any desired construction. Since the mount-
ing of the cutters is exactly the same, it is be-
lieved a description of one will suffice. 30

Each cutter is provided with an enlarged cylind-
rical axial bore 19 which is arranged to fit over
the axle shaft. The bore has a diameter greater
than the diameter of the axle whereby when the
axle is inserted in the bore, an annular space 20 35
is provided between the outer surface of said
axle and the inner surface of the bore. The depth
of the bore is substantially equal to the length
of the axle and the bottom of the bore is provided
with an annular groove 21, semi-circular in cross- 40
section and complementary to the annular groove
16 in the axle. Thus, when the axle is inserted
in the bore, the grooves register, whereby a race-
way is formed to receive ball bearings 22. These
balls being at the bottom of the axle absorb the 45
longitudinal thrust upon the cutter.

For rotatably securing each cutter to its axle,
the inner wall of the bore of each cutter, is
formed with annular ridges or corrugations 24
which are complementary to the corrugations 15 50
of the axle, whereby corrugated rollers 25 may be
inserted in the annular space 20 around the axle.
The rollers are entered into the space 20 through
an inclined cylindrical opening 26 in the hanger
or leg of the bit. A portion of the corrugations 55

15 and 24 are cut away at 27 (Figure 2) to permit insertion of the rollers, and thus, it will be seen that sufficient rollers may be entered to completely fill the space 20. After the rollers are in place, an elongated pin 28 is placed in the opening 26 and is of sufficient length so that its lower end terminates in alignment with the inner inclined side 18' of the hanger member 13. The pin is welded, or otherwise secured, in said opening and serves to prevent the roller in the cut-out portion 27 from being displaced upwardly. It is obvious that the engagement of the corrugations of the roller with the corrugations of the bore and axle rotatably hold each cutter on its axle.

In this type of drill bit, the conical cutters 17 rotate to perform the cutting operation upon the slippery bottom of the well hole only by the traction of their teeth and therefore, it is essential that bearing friction be reduced to a minimum. It is obvious that with the elongated corrugated rollers and the ball bearings, bearing friction is greatly reduced and also due to the length of the rollers, the bearing area is greatly increased because rollers will outwear ball bearings which are usually employed in the ordinary cone cutter drill.

Since the bottom of the cone performs the cutting operation, there occurs an increased upward thrust against the rollers 25. The corrugations are so formed that one of the surfaces 25' of each corrugation is substantially at a right angle to the direction of this thrust, as shown by arrows in Figure 6. There, these surfaces 25', co-acting with the registering corrugations of the rollers and shaft, take the thrust and since a plurality of corrugations are provided an increased thrust area, throughout the length of the bore is provided. Further, the corrugations provide an increased bearing area which increases the life of the bit. From the above, it will be seen that the ball bearings take any longitudinal thrust and also make for easier rotation of the cutters, while the elongated rollers absorb the transverse thrust and provide increased bearing surface. The entire bit may be readily dismantled by merely removing the pin 28 and then removing the rollers. Assembling is just as quick and simple.

In Figures 3 to 6, I have shown another form of the invention. In this form the axles are made separate from the body which is formed with circular hanger members 30 having inclined inner surfaces 30'. The hanger members are preferably integral with the bit body and are reinforced by webs 31. The lower end of each web and the hanger is formed with a rectangular slot 32 which is arranged to receive a central triangular shaped rib 33 formed on the outer side of a circular plate 34. When the rib is inserted in the slot, the plate lies contiguous to the inner face 30' of the hanger, as clearly shown in Figure 3. Depending axially from the plate is the cutter axle 14 which is arranged to be inserted in the bore 19 of the cutter. Each cutter is rotatably secured to the axle in this form in the same way as in the form shown in Figures 1 to 3, the corrugated rollers 25 being inserted in the space 20 through an inclined opening 35 in the rib 33. A short pin 36 closes said opening.

The advantages of the first form are present in this form since the same means of mounting each cutter on its axle is employed. However, in this latter form the cutters may be mounted on the axles before said axles are fastened to the bit body. This feature makes for more con-

venient assembling and dismantling of the entire bit.

It is pointed out that no claim is made in this application to the particular actuation of the cone, as said cone may have any actuation, either as shown herein or as set forth in my Letters Patent No. 2,020,625, issued November 12, 1935, in which the invention herein is employed as a mounting.

What I claim and desire to secure by Letters Patent is:

1. A drill bit including, a body, axles carried by the body, a conical cutter arranged to be mounted on each axle and having a bore for receiving the axle, and roundingly corrugated rollers located in the bore of each cutter and surrounding each axle for rotatably mounting each cutter and retaining it with thrust resistance on its axle.

2. A drill bit including, a body, axles carried by the body, a conical cutter arranged to be mounted on each axle and having a bore for receiving the axle, roundingly corrugated rollers located in the bore of each cutter and surrounding each axle for rotatably mounting each cutter on its axle, the wall of said bore being correspondingly annularly grooved to receive said rollers, and means in the body for introducing said rollers one at a time into the bore of each cutter after said cutter has been placed on its axle.

3. A drill bit including, a body, axles carried by the body, a conical cutter arranged to be mounted on each axle and having a bore for receiving the axle, and roundingly corrugated rollers located in the bore of each cutter and surrounding each axle for rotatably mounting each cutter on its axle, the wall of said bore being correspondingly annularly grooved to receive said rollers, said body having an opening adjacent each body axle and cutter bore whereby the rollers may be introduced one at a time into the bore of each cutter after said cutter has been placed on its axle.

4. A drill bit including, a body, axles carried by the body, a conical cutter arranged to be mounted on each axle and having a bore for receiving the axle, roundingly corrugated rollers located in the bore of each cutter and surrounding each axle for rotatably mounting each cutter on its axle, the wall of said bore being correspondingly annularly grooved to receive said rollers, said body having an opening adjacent each body axle and cutter bore whereby the rollers may be introduced one at a time into the bore of each cutter after said cutter has been placed on its axle, and a closure plug insertable in the openings for preventing outward displacement of the rollers.

5. A drill bit including, a body, diametrically opposite hangers at the lower end of the body, an inclined axle carried by each hanger, a conical cutter arranged to be mounted on each axle and having a bore for receiving the axle, and roundingly corrugated rollers located in the bore of each cutter and surrounding each axle for rotatably mounting each cutter on its axle and the body axle and cutter bore being correspondingly annularly grooved to receive said rollers.

6. A drill bit including, a body, axles carried by the body, a conical cutter arranged to be mounted on each axle and having a bore for receiving the axle, each axle and bore having complementary rounded corrugations, and elong-

gated correspondingly roundingly corrugated rollers adapted to fit within the bore of each cutter and around its axle and arranged to engage the corrugations thereof to hold each cutter 5 on its axle and to provide increased area for bearing the transverse and diagonal thrust on each cutter.

7. A drill bit including, a body, axles carried by the body, a conical cutter arranged to be 10 mounted on each axle and having a bore for receiving the axle, roundingly corrugated rollers located in the bore of each cutter and surrounding each axle for rotatably mounting each cutter on its axle, the body axle and cutter bore being correspondingly corrugated to receive said roundingly corrugated rollers, and ball bearings disposed in the bottom of the bore of each cutter and engaging the lower end of the axle for resisting end thrust and reducing the friction during rotation of the cutter. 20

8. A drill bit including, a body, removable axles carried by the body, a conical cutter arranged to be mounted on each axle and having a bore for receiving the axle, and corrugated rollers located in the bore of each cutter and surrounding each axle for rotatably mounting each cutter on its axle. 5

9. A drill bit including, a body, axles removably attached to the lower end of the body, a conical cutter arranged to be mounted on each 10 axle and having a bore for receiving the axle, said bore having a diameter greater than the axle whereby an annular space is formed around the axle, the axle and bore having complementary annular corrugations, and corrugated rollers inserted in said annular space, the corrugations of the rollers serving to hold the cutters on the axles. 15
